UNITED STATES PATENT OFFICE.

MATTHIAS F. MOHR, OF PLANTSVILLE, CONNECTICUT.

HANDLE-FASTENER.

No. 895,389.

Specification of Letters Patent.

Patented Aug. 4, 1908.

Application filed March 5, 1908. Serial No. 419,322.

To all whom it may concern:

Be it known that I, MATTHIAS F. MOHR, a citizen of the United States, residing at Plantsville, in the county of Hartford and State of Connecticut, have invented a new and useful Improvement in Handle-Fasteners; and I do hereby declare the following, when taken in connection with the accompanying drawings and the letters of reference marked theron, to be a full, clear, and exact description of the same, and which said drawings constitute part of this specification, and represent, in—

Figure 1 a side view of a screw driver constructed in accordance with my invention, with the grip removed. Fig. 2 a longitudinal sectional view at right angles to Fig. 1. Fig. 3 a sectional view showing the shank interlocked with the handle. Fig. 4 a sectional view on the line *a*—*b* of Fig. 2. Fig. 5 a sectional view of tool with square shank.

This invention relates to an improvement in handle fasteners for screw drivers and kindred tools, that is, tools having a shank entered into a handle; and the invention particularly relates to means for securing the shank in the handle and consists in the construction hereinafter described and particularly recited in the claims.

In carrying out my invention, I provide a handle frame consisting of a central web 2, ferrule shaped end 3 and butt or bolster 4. Extending longitudinally through the ferrule end 3 is a hole corresponding in shape to the shape of the shank 6 of the tool either round as shown in Fig. 2 or square as shown in Fig. 5. The inner end of this shank is notched, forming fingers 7 and 8 and preferably the edge of the web 2 which is in line with the hole 5 will be slightly tapered. In assembling the parts the shank 6 is driven through the ferrule into the handle and so that the fingers 7 and 8 will pass on opposite sides of the central web 2, and as the shank is driven home these fingers will be separated or turned

against the inner face of the ferrule end, as clearly shown in Fig. 3 of the drawings so as to interlock the shank of the tool with the handle. Grips of wood or other suitable material will be secured to the web 2 in the usual manner.

Another part of my invention relates to the construction of the grip portion and consists in providing the edge of the web with flanges 9 and 10 on opposite sides into which the edges of the grips 11 and 12 will extend so that in case the grips shrink they will not form an opening liable to injure the hand of the operator.

I claim:

1. A handle fastener for screw drivers or kindred tools comprising a handle having a ferrule shaped end and a butt end or bolster, a longitudinal central web connecting the ends, and opening through said ferrule end in line with said web, combined with a shank having a notched end adapted to pass through said ferrule end and onto said web whereby the ends of the shank are turned outward and locked against the inner face of the ferrule end.

2. A handle fastener for screw drivers or kindred tools comprising a handle having a ferrule shaped end and a butt end or bolster, a longitudinal central web connecting the ends, an opening through said ferrule end, the edge of the web in line with said opening tapered, combined with a shank having a notch at its inner end, said shank adapted to be forced through said ferrule end and onto the web whereby the ends of the shank are turned outward and locked against the inner face of the ferrule end.

In testimony whereof, I have signed this specification in the presence of two subscribing witnesses.

MATTHIAS F. MOHR.
